INTERLOCKED DUPLEX BROACHING MACHINE

Kenneth C. Monroe, Hudson, Mass., assignor to
The Lapointe Machine Tool Company, Hudson,
Mass., a corporation of Maine

Application February 23, 1938, Serial No. 192,118

9 Claims. (CL. 90—33)

This invention relates to duplex broaching machines which are hydraulically operated and in which two broaching rams or slides are moved alternately and simultaneously in opposite directions.

It is the general object of my present invention to provide actuating mechanism and control devices for such a broaching machine, so designed and correlated that the machine may be conveniently controlled and operated, but only according to a predetermined sequence of steps.

More specifically, I provide control devices so interlocked that the work clamping devices, the fixture slide and one or the other of the broaching rams must all be in correct operative relation before a working stroke of said ram can take place.

My invention further relates to arrangements and combinations of parts which will be herein-after described and more particularly pointed out in the appended claims.

A preferred form of the invention is shown in the drawings, in which

Fig. 1 is a diagrammatic plan view of my improved broaching machine, with certain parts in section and with the machine at rest and in loading position;

Figs. 2 and 3 are partial diagrammatic views showing the relation of certain parts at successive points in the cycle of machine operation; and

Fig. 4 is a view similar to Fig. 1 but showing the parts in working position.

The broaching machine shown in the drawings is of the duplex hydraulic type and is designed to clamp the work in a fixture slide by hydraulic pressure and to maintain the work thus clamped during successive broaching operations by two broaching rams or slides.

Referring to Fig. 1, I have indicated broaching rams or slides A and B connected to pistons 20 and 21 slidable in main cylinders 22 and 23. These cylinders are connected by pipes 24 and 25 to a pump P which is of the reversible discharge type, such as is shown for instance in the patent to West No. 1,722,832.

The direction and rate of discharge of the pump P is controlled by a pinion 26 and rack 27, and the rack is connected to a main control lever 28 pivoted at 29 and having a handle 30 by which it may be manually operated. The lever 28 is also connected to a piston 31 in a main control cylinder 32.

A knock-off rod 33 is connected through a lever 34 and link 35 to the control lever 28 and is

provided with an adjustable knock-off collar 36 adapted to be positioned for engagement by an arm 37 on the ram A as the ram approaches the end of its downward or working stroke. By such engagement, the control lever 28 is returned to 5 mid or neutral position, in which position there is no discharge of the pump P in either direction.

A second knock-off rod 38 is connected by a lever 39 and link 40 to the extended end of the control lever 28 and is provided with an adjustable collar 41 positioned for engagement by an arm 42 on the ram B as said ram B approaches the end of its downward or working stroke.

The lower ends of the cylinders 22 and 23 are connected by a pipe 43 having a needle valve 15 43a by which back pressure is provided and controlled.

A solenoid operated valve V is provided for the control cylinder 32, and liquid under pressure is supplied to the valve V by an auxiliary pump 20 P', the surplus discharge from which is returned to a reservoir R through a relief valve 44. The discharge from the control cylinder 32 is delivered to the reservoir R through an exhaust pipe 45, and the rate of movement of the valve 25 is controlled by a needle valve 46.

A fixture slide 50 is associated with a fixture slide cylinder 51 mounted to slide on a fixed piston rod 52 and relative to a fixed piston 52a. The fixed piston rod 52 is hollow at both ends 30 but closed where the piston is mounted and is provided with ports adjacent the piston which open into the opposite ends of cylinder 51. The cylinder 51 and slide 50 are movable from a right-hand to a left-hand working position or 35 vice-versa in accordance with the application of pressure to one end or the other of the fixed piston rod 52.

Oil under pressure is supplied to the hollow rod 52 through pipes 53 and 54 which are connected to a valve V' which in turn receives oil under pressure from a pump P' through a pipe 55. Excess discharge of the pump P' is returned to the reservoir R through a relief valve 56, and the rate of flow through the pipe 55 to the cylinder 51 may be controlled by a needle valve 57. Back pressure in the idle end of the cylinder 51 is provided by a relief valve 58.

The fixture slide valve V' is provided with a handle 60 by which it may be manually operated. The handle 60 is, however, normally locked in one position or the other by a plunger 61 slideable in a solenoid coil 62. When the solenoid is energized, the plunger is withdrawn and the valve may be shifted but when the solenoid cir- 55

cuit is open, the handle 60 and valve V' are locked against manual movement. The control of the solenoid 62 will be hereinafter described.

The two ends of the fixture cylinder 51 are connected through check valves 64 and 65 to a valve V² which in turn is connected through pipes 66 and 67 to the opposite ends of a work clamping cylinder 68 in which a piston 69 is slideable. The piston 69 is connected to the work-clamping devices (not shown) and these clamping devices are free when the piston 69 is in raised position, as shown in Fig. 1. The work is clamped when the piston 69 is in the lowered position shown in Fig. 2. The valve V² is manually operated by a handle 70. Back pressure on the piston 69 is provided by a needle valve 71.

The valve **V²** and work clamping devices including the clamping cylinder **68** are all mounted to move with the fixture slide **50** and cylinder **51**. This construction has the great advantage that oil under pressure is not transmitted through connections between relatively moving parts. Outside connections are made only through the fixed piston rod **52**.

Having described the main features of my improved broaching machine and the hydraulic actuating mechanism therefor, I will now describe the interlocking electrical connections by which the sequence of operations is predetermined.

30   **Fixture switches 80 and 81** are provided, which switches are normally open but are closed alternately by the fixture slide 59 when the slide is in one or the other of its right-hand and left-hand working positions. Limit switches 82 and 83 are closed only when engaged by cam plates 84 and 85 on the broaching rams A and B, when one or the other of the rams is in upper or withdrawn position at the end of its return stroke.

40 The limit switch 82 is a double pole switch separately controlling one circuit through the fixture switch 80 and a second circuit through a solenoid coil 86 which may be energized to raise a plunger 87 to clear a plate 88 on the side of the handle 70.

45 The fixture switch 81 is also a double pole switch, one part of which controls a circuit through the solenoid operated valve V. The second part of the switch 81 is in series with one part of the switch 82 in the circuit of the solenoid 86.

50 Current is derived from line wires 90 and 91, and a manually operated switch or push button 92 is inserted in the line 91. An additional switch 94 is associated with the work clamping cylinder 68 in such manner that the switch 94 is open when the piston 69 is raised and the work is released but is closed when the work is clamped.

The parts are shown in Fig. 1 in work-loading position, with the ram A raised, the ram B lowered, the fixture slide 50 in right-hand or loading position, and the piston 69 raised so that the work-clamping devices are open or withdrawn.

The double pole limit switch 2 is closed by the cam plate 84 and the double pole fixture switch 81 is closed by the fixture slide 50. The main control lever 28 is in mid position and the pump 65 P is in no-discharge position.

After the work has been placed on the fixture slide 50, the operator moves the handle 70 from the position shown in Fig. 1 to the position shown in Fig. 2, reversing the pressure connections to the cylinder 68 and causing the piston 69 to move downward and clamp the work. As this downward movement takes place and the work is clamped, the switch 94 is closed.

75 The operator then closes the manual switch 92,

thus completing the circuit through the switch 92, solenoid 62 and switch 94, and withdrawing the locking solenoid plunger 61. This releases the valve lever 60. The operator thereupon moves the lever 60 from the position shown in Fig. 1 to the position shown in Fig. 3, thus reversing the connections in the valve V' and applying pressure in the left-hand end of the fixture cylinder 52, thus moving the fixture slide 50 to the left-hand position shown in Fig. 3, which is its working position in relation to the ram A. As the slide 50 reaches its extreme left-hand position, it engages and closes the switch 80. The switch 81 opens as the fixture slide moves to the left, breaking the circuit through the solenoid coil 86 and releasing the plunger 87 which moves down and locks the handle 70 against movement to unclamp the work.

The closing of the switch 80 by the fixture slide 50 and the previous closing of the limit switch 82 by the cam plate 84, in conjunction with maintaining the switch 92 closed by the operator, completes the circuit through the solenoid operated valve V, thereby causing the valve to shift its connections to operate as shown in Fig. 3, supplying oil under pressure to the upper end of the control cylinder 32 and shifting the main control lever 28 to the position shown, in which the pump P supplies oil under pressure to the upper end of the main cylinder 22, thus causing the ram A to move downward on its operative or broaching stroke. As soon as the ram A starts to move downward, the operating circuit of the solenoid in the valve V is broken by the opening of the switch 82 and the valve returns to mid or neutral position but the lever 28 remains in the position of Fig. 3. The operator can now release his pressure on the switch 92 as the circuit of the solenoid 62 is also broken by the opening of the switch 82 and the lever 60 is locked in the position shown in Fig. 3.

At the end of the down stroke of the ram A, the arm 37 will engage the knock-off collar 36 and will move the main control handle 28 back to the neutral or no-discharge position shown in Fig. 1. At the same time the cam plate 85 on the ram B will engage and close the limit switch 83, but the reverse operating circuit for the control valve V is not completed, as the fixture slide 59 is still in left-hand position and the switch 81 is open.

The operator now closes the hand switch 92, thus releasing the handle 60, which is then moved manually to reverse the connections of the fixture slide valve V' as shown in Fig. 4, thereby admitting oil under pressure to the right-hand end of the cylinder 52 and moving the fixture slide 50 toward the right.

slide 50 toward the right. As this movement is completed, the slide engages and closes the switch 81, thus completing the reverse circuit for the solenoid operated valve V. The valve V is thereon shifted to admit oil under pressure to the lower end of the control cylinder 32, moving the main control lever 28 and rack 27 to the position shown in Fig. 4, and thereby causing the pump P to deliver oil under pressure to the upper end of the cylinder 23, thus giving the ram B a downward or operative broaching stroke.

As soon as this movement is begun, the cam plate 85 moves away from the switch 83, which automatically opens, breaking the circuit through the solenoid operated valve V, and also deenergizing the solenoid 62. The plunger 61 then locks the lever 60, now back in the position shown in Fig. 1. During all of these operations, the lever 75

70 which controls the clamping devices is locked in the position shown in Figs. 2 and 4 and the work cannot be unclamped.

When the working stroke of the ram B is completed, the arm 42 engages the knock-off collar 41 and restores the control lever 28 and rack 27 to neutral position, the solenoid circuit of the valve V having been previously opened as described, and the valve V being in neutral position. Completion of the second working stroke brings the ram A back to raised position and closes the switch 82.

Two successive broaching operations on the work having been now completed, the operator 15 closes the hand switch 92 to withdraw the plunger 87 and then shifts the handle 78 back to the left-hand position shown in Fig. 1, thereby connecting the oil supply to the lower end of the cylinder 68 and causing the piston 69 to move upward and 20 return to the position shown in Fig. 1. This opens the switch 94 and releases the work-clamping devices.

The parts are now restored to their initial position, with the ram B at the bottom of its working stroke and with the fixture slide 50 in its right-hand position for removal of the finished work and insertion of a new piece of work 25 therein.

Having thus described the construction and 30 cycle of operations of my improved interlocked duplex hydraulic broaching machine, the advantages thereof will be readily apparent. The lever 60 cannot be unlocked until the work has been clamped on the fixture slide by means of the handle 78, thereby closing the switch 94.

After the work has been clamped, the handle 60 can only be released by closing the hand switch 92, after which the valve V' can be manually reversed, causing the fixture slide 50 to 40 move to its left-hand position. As this position is reached, the switch 80 is closed, thereby causing the ram A to make its working stroke and to thereafter come to rest. The handle 60 can then be released by again closing the switch 92. 45 By again manually moving the valve V', the fixture slide can be moved to the right-hand position for a broaching operation by the ram B.

During all of this time, the work must remain 50 clamped in the fixture, as the handle 78 can only be released from its clamping position when the ram A is up and the fixture slide is in right-hand or loading position.

The interlocking control devices above described safeguard the broaching machine, the 55 broaches and the work itself, as they prevent any improper sequence of operation of the hydraulically actuated means, and prevent the machine from operating at all if the work is not clamped or if the fixture slide is not correctly 60 and accurately positioned. By the use of my improved machine with its interlocking control devices, I am able to carry out progressive broaching operations on a piece of work, with certain operations performed by the action of one ram 65 and other operations performed by the action of the other ram and with all of the operations performed while the work remains securely clamped in the fixture slide. I am thus able to economically produce very accurate work, utilizing both rams of a duplex hydraulic broaching machine.

Having thus described my invention and the advantages thereof, I do not wish to be limited to the details herein disclosed, otherwise than as 75 set forth in the claims, but what I claim is:

1. A duplex broaching machine comprising a pair of alternately operative and oppositely moving broaching rams, a fixture slide, a device to clamp a piece of work thereon when said slide is in loading position, means to move said slide transversely to present said piece of work while clamped thereon successively in operative relation to both of said rams and to return said work to loading position, and control devices operatively interlocking said rams, slide and clamping 10 device, so that no movement of said rams or slide can occur until the clamping device has been rendered operative.

2. A duplex broaching machine comprising a pair of alternately operative and oppositely moving broaching rams, a fixture slide, a device to clamp a piece of work thereon when said slide is in loading position, means to move said slide transversely to present said piece of work while clamped thereon successively in operative relation to both of said rams and to return said work to loading position, and control devices operatively interlocking said rams, slide and clamping device, so that the fixture slide can be moved only with the work clamped and with the rams in 20 predetermined positions.

3. A duplex broaching machine comprising a pair of alternately operative and oppositely moving broaching rams, a fixture slide, a device to clamp a piece of work thereon when said slide is in loading position, means to move said slide transversely to present said piece of work while clamped thereon successively in operative relation to both of said rams and to return said work to loading position, and control devices operatively 30 interlocking said rams, slide and clamping device so that the work cannot be unclamped until a cycle of successive broaching movements by both rams has been completed.

4. A duplex broaching machine comprising a pair of alternately operative and oppositely moving broaching rams, a fixture slide, a device to clamp a piece of work thereon when said slide is in loading position, means to move said slide transversely to present said piece of work while clamped thereon successively in operative relation to both of said rams and to return said work to loading position, and control devices operatively 40 interlocking said rams, slide and clamping device so that the work cannot be unclamped until the rams and slide have been returned to loading 45 position.

5. A duplex broaching machine comprising a pair of alternately operative and oppositely moving broaching rams, a fixture slide, a device to clamp a piece of work thereon when said slide is in loading position, means to move said slide transversely to present said piece of work while clamped thereon successively in operative relation to both of said rams and to return said work to loading position, and control devices operatively 55 interlocking said rams, slide and clamping device, so that the fixture slide can be moved transversely only when the work is clamped.

6. A duplex broaching machine comprising a pair of alternately operative and oppositely moving broaching rams, a fixture slide, a device to clamp a piece of work thereon when said slide is in loading position, means to move said slide transversely to present said piece of work while 60 clamped thereon successively in operative relation to both of said rams and to return said work to loading position, and control devices operatively 65 interlocking said rams, slide and clamping device, so that the clamping device must be ren- 70 set forth in the claims, but what I claim is:

dered operative before either ram can be moved from its limit of travel.

7. A duplex broaching machine comprising a pair of alternately operative and oppositely moving broaching rams, a fixture slide selectively movable transversely to operative relation with a selected ram, a cylinder secured to said slide, and a fixed piston and piston rod relative to which said cylinder is slidable, said piston rod having 10 separated passages in its two ends each connected to admit oil under pressure to one end of said cylinder and at one side of said fixed piston.

8. In a duplex broaching machine, a fixture slide movable to two selective operative positions, 15 a hydraulic cylinder and piston cooperating to move said slide, a work-clamping cylinder mounted on said slide, a control valve for said latter cylinder, and connections open continuously from both ends of said fixture slide cylinder to the in-
20

take of said control valve, whereby pressure is maintained on said control valve whenever pressure exists in either end of said cylinder.

9. In a duplex broaching machine, a fixture slide movable to two selective operative positions, 5 a hydraulic cylinder and piston cooperating to move said slide, a work-clamping cylinder mounted on said slide, a control valve for said latter cylinder, and connections open continuously from both ends of said fixture slide cylinder to the intake of said control valve, said connections being branched to the two ends of said fixture slide cylinder and each branch having a check valve opening away from said cylinder, whereby 10 pressure is maintained on said control valve whenever pressure exists in either end of said cylinder. 15

KENNETH C. MONROE.
